DRIVE MECHANISM FOR QUILTING MACHINES
David R. Cash, Louisville, Ky., assignor to James
Cash Machine Co., Louisville, Ky., a corporation
of Kentucky

Filed Apr. 4, 1962, Ser. No. 185,041
4 Claims. (Cl. 112—118)

This invention relates generally to quilting machines, and particularly to a novel means for providing a positive drive and obtaining intricate quilt stitch patterns.

In many bedding components, including mattresses as well as bed covers, quilting is found desirable both from the appearance and functional standpoints. Quilting can be accomplished by machines which are well known in the art. However, the nature of the quilt stitch pattern has heretofore been quite limited by the inability of available machines to provide patterns having sharp changes of direction or having crossing stitch paths.

While efforts have been made to overcome the inability of quilting machines to produce patterns having intersecting rows of stitches, little or no success has been achieved heretofore. One significant disadvantage of available machinery is the fact that the stitch they produce is irregular, particularly at sharp changes of direction.

It is a general object of the present invention to provide means for increasing versatility of quilting machines.

It is a further object of the present invention to provide means for ensuring regularity of stitches in an intricate stitch pattern for quilting.

It is a still further object of this invention to provide means for achieving the foregoing objects and enabling the same to be achieved in the execution of a quilt stitching operation where the quilt pattern includes a number of intersecting rows of stitches.

It is a still further object of the present invention to provide means for achieving the foregoing objects, which means can be employed in a variety of existing quilting machines.

Described briefly, a typical embodiment of the present invention includes a pattern track having a base plate and intersecting rows of upstanding teeth in an endless pattern secured to the plate. A novel tracer head is provided with an input shaft to be coupled to the quilting machine drive motor and an output drive gear engaging the pattern track. The head incorporates novel drive means for maintaining engagement between the drive gear and the track while at the same time avoiding torques which would tend to interfere with the retention of proper engagement with the track.

The full nature of the invention will be understood from the accompanying drawings and the following description and claims:

FIG. 1 is a perspective schematic illustration of an automatic quilting machine of the type employed in the manufacture of quilted mattresses.

FIG. 2 is a top plan view of a pattern track according to a typical embodiment of this invention.

FIG. 3 is a side elevation, partially in section, of the novel drive head of the present invention engaged with a portion of the pattern track, all of the elements of FIG. 3 being greatly enlarged by comparison with FIG. 1.

FIG. 4 is a vertical section taken along the line 4—4 of FIG. 3.

FIG. 5 is an enlarged fragmentary side elevation illustrating details of engagement of the track drive gear and track at a track intersection.

FIG. 6 is a fragmentary section taken along line 6—6 of FIG. 5 with the driving gear omitted and illustrating a second aspect of the track intersection.

FIG. 7 is an enlarged fragmentary illustration of the drive gear and retainer assembly.

2

Quilting Machines in General (FIG. 1)

Typical quilting machines include a stationary frame having uprights 12 and 13 connected by lower, intermediate, and upper cross members 14, 16 and 17, respectively. A sewing machine 18 is mounted to the upper cross member and driven by a shaft 19 extending from the upright 12 and driven by a motor therein. The upper sewing head 21 of the sewing machine is located in the usual location with respect to the material to be sewn and includes the sewing needle.

5 A movable carriage 22 is mounted to the stationary frame in such a manner that it is free to move in any direction in a horizontal plane. For movements parallel to the frame cross members 14 etc. support tracks 23 and 24 which rest on the floor and are secured to the uprights 12 and 13, carry the roller wheels 25 at each end of the carriage. Wheels 26 provide the support for the carriage lower support frame having side members 27. The side members 27 support the wheels 28 which are mounted to the carriage upper support frame 29 to allow movements of the carriage perpendicular to the cross member 14.

20 On the top frame of the carriage, materials 31 to be sewn together in a quilt pattern are held in place by the clamps 32. These materials, for example, might include a layer of ticking, a layer of felt, a layer of padding material and another layer of felt and a web base.

25 Immediately below the materials to be sewn, and mounted to the cross member 16 in alignment with the head 21 of the sewing machine, is the usual thread locking mechanism (not shown in the drawing).

30 A pattern track 33 is removably secured to the carriage upper support frame 29. The pattern track includes a base plate with a track 34 thereon which is laid out in the pattern of the quilt stitch pattern desired.

35 A drive head 36 has a drive member 37 engaging the track 34 at a point immediately below the drive shaft 38. The shaft 38 is driven from a suitable transmission 39 receiving its drive from the drive motor 41, both the transmission and drive motor being mounted to one of the cross members and, therefore, stationary. Thus, power is coupled from the motor 41 to the drive member 37 whereby it is capable of driving the track and thereby the carriage in the many different directions required to obtain the desired quilt stitching pattern. Of course, the mounting of the drive head 36 to the shaft 38 permits the head to turn to whatever extent is necessary as it drives the pattern track.

50

Pattern Track (FIGS. 2-6)

According to the present invention, the pattern track assembly includes a base plate 51 and elongate strips 52 mounted on edge thereon and provided with upstanding teeth 53 at the upper margin thereof. Many forms of teeth or other types of positive drive elements including pins and apertures, for example, may be found suitable. However, an involute form is excellent in which case the strips 52 may be understood to provide an involute gear rack. The expressions "tooth" and "teeth" will, however, be used generically in the claims herein and understood to contemplate other types of positive drive elements.

55 The teeth extend in succession in a layout having the pattern desired in the quilt. The succession of teeth is endless so that the drive head can begin driving the carriage at any point on the track and continue to drive the pattern until the quilting is completed without ever retracing the stitch.

60

65 In FIG. 2, taking the point 56 as a starting point and assuming the track is driven in the direction of arrow 57, the movement of the head with respect to the pattern

track along the leg 58 of the track, is in the opposite direction shown by arrow 59. The head then negotiates the turn 61 and drives along the straight leg 62. The drive continues back and forth to the opposite end of the pattern track and then crosswise thereof as it follows the serpentine layout of the track. It is the track, of course, which is moved in horizontal translation and not the head. It should be understood that a wide variety of patterns other than that shown in FIG. 2 may be employed. The rows of teeth need not be straight and intersections of rows of teeth need not be right-angle intersections.

In FIG. 5, one view of an intersection such as intersection 63 of FIG. 2, is illustrated. A tooth 64 is provided at the precise center of the intersection and the next adjacent tooth 53a on one side and 53b on the other side is placed from the center tooth 64 a distance equal to the sum of the length of tooth 53 and two tooth spaces 66. This is to provide for passage of the drive member (to be described hereinafter) across the intersection in a direction perpendicular to the direction of the row of teeth illustrated. It will be recognized, that by use of the construction illustrated in FIG. 5, a long strip 52 of material with suitable cut aways 67 and 68 at the intersections can be welded to the plate 51 and thereby facilitate the manufacture of the pattern track.

From the foregoing it will be appreciated that my pattern track assembly comprises: a base plate 51; and an elongate track 52 secured to said base plate, said track being composed of an elongate strip of material, also 30 designated 52. This strip has straight sections 58 and 62, curved sections 61 and intersections 63 respectively corresponding to the straight and curved sections and intersections of a desired quilt-stitching pattern. The strip 52 presents, between intersections, an upper edge notched to provide a uniform succession of teeth 53. The strip has, at one intersection, one track section extending continuously through the intersection (as indicated at the bottoms of cut aways 67 and 68 in FIG. 5) with one tooth 64 (on that extension) centered on that intersection and with the upper margin of that extension cut away to eliminate one tooth on each side of said centered tooth. At the same intersection, the other track section of the strip has one tooth centered on that intersection and is arranged with its upper margin cut away to eliminate the centered tooth and one tooth on each side thereof.

In FIG. 6, which views the intersection 63 at 90° with respect to FIG. 5, it will be observed that to obtain the sections of track which cross the track 52, it is convenient to provide them in separate sections 52a and 52b welded to the base plate.

Drive Head (FIGS. 3 and 4)

The drive head 70 includes a housing 71 with the cover plate 72 secured thereto by the screw 73. The drive shaft 74 is mounted in the housing by means of a bearing 71a (partially shown). It will be recognized, therefore, that the housing is free to rotate with respect to the shaft 74 and vice versa, but is not free to move axially with respect to the shaft 74 by any more than the necessary bearing tolerance. The upper end of the shaft 74 is provided with a keyway 74a whereby rotational drive can be provided from the motor 41.

A worm tooth 75 (usually 24:1) is provided at the lower end of the shaft 74 and drives the gear 76 mounted for rotation in the housing on shaft 77. By the employment of worm and gear in this fashion, the torque on the housing caused by the input drive is made negligible.

A second shaft 78 supports the drive member 79 for rotation in the housing in a plane on the axis of the input shaft 74. The shaft 78 intersects the axis of shaft 74, whereby the drive point between the drive member 79 and the pattern track is in line with the axis of input shaft 74, again avoiding any torque on the housing resulting from the drive.

Summarizing the foregoing description of the drive head 70, it will be appreciated: that I provide a motor-driven follower of the type used for shifting a quilting-machine carriage means in accordance with the straight and curved sections of a pattern forming track 52 traversed by the drive head or follower 70. This follower comprises: a follower housing 71; and a drive train supported by the housing. The drive train includes: a power input shaft 74 extending vertically downward into said housing; a track-engaging gear 79 mounted for rotation about the transverse axis of a shaft 78; interconnecting means for driving the track-engaging gear 79 from shaft 74 (including worm 75, shaft 77, gear and sprocket combination 76 and 88, chain 89 and sprocket and gear combination 91 and 79 on shaft 78); a pair of wheel-like flanges 81, 82, one mounted on each side of the track-engaging gear 79 for rotation about the axis of shaft 78, one of said flanges being axially movable in relation to the other; and resilient means 83 interposed between an inner wall of the housing and movable flange 82 to bias that flange toward the other flange 81.

While the drive member 79 may employ transverse pins to engage the track teeth, it is most convenient to use an involute gear, a 20:12 gear being well suited for the purpose.

Gear 79 is flanked on opposite sides by wheel-like flanges 81 and 82. These flanges maintain the alignment of the gear with the track. To accommodate a turn in the track, the inside faces 81a and 82a of the flanges are convex in form and the flange 82 is allowed to move axially with respect to the flange 81. To maintain the minimum spacing between the flanges at all times when the head is driving a straight portion of track and permit separation to the extent necessitated by the degree of curvature where a curved portion of track is encountered, a spring 83 is disposed between the housing wall 84 and the flange 82.

A convenient construction of the drive member and flange unit is illustrated in FIG. 7. The gear 79 is slightly inset into a circular cavity 81b in the flange 81 and secured to the flange by means of pins 86. Flange hub 87 is keyed to the shaft 78 and secured by a setscrew.

A similar cavity 82b is provided in flange 82 and the face of gear 79 may lie in abutting relation to the face of cavity 82b when the gear is operating on a straight portion of track. By virtue of the sliding fit of the flange hub 82c on shaft 78, the spacing of the flanges can increase as the gear encounters a curve in the track. By way of example, a typical amount of movement encountered may be from $\frac{3}{16}$ to $\frac{5}{32}$ of an inch.

A sprocket 88, secured to shaft 77, is driven by the gear 76 and drives chain 89 to drive sprocket 91 secured to shaft 78 which in turn drives the gear 79. A chain tensioning idler 92 is adjustably mounted in the housing 71 to provide suitable chain tension.

From study of the illustrated embodiment of FIG. 4 it can be appreciated that the drive head is statically balanced with respect to a plane including the axis of the input shaft and perpendicular to shafts 77 and 78. 60 This is accomplished by location of parts and providing a thicker section in wall 84 than is provided in the facing wall of the housing. Thus wall 84 and the spring 83 balance the weight of the sprockets, chain and idler shaft. The tracking capability of the drive head is thereby improved. It should be understood, of course, that the housing need not be of the specific shape illustrated.

From FIG. 5, an interesting detail of the drive at intersections can be observed. Assuming that the track is being driven in the direction of arrow 96, drive gear 79 70 is rotating clockwise as indicated by arrow 97. To avoid applying an excessive drive load on the center tooth 64, the gear and track teeth are cut and spaced such that gear tooth 79a enters into driving contact with rack tooth 53b before gear tooth 79b discontinues driving contact 75 with rack tooth 53a. Center tooth 64 can thus function

principally for alignment by cooperation with the retainer flanges (31, 32, FIG. 4).

Conclusion

It will be appreciated from the foregoing description, 5 that by the provision of positive drive means, both in the pattern track and in the drive head, the stitch pattern obtained in a quilting machine employing the present invention will have uniform length. By virtue of the special provisions taken to avoid a torque on the housing 71 resulting from power transmission, true tracing of the pattern by the drive head is obtained, avoiding wavering 10 of the stitch and assuring precise control over all intersections. The additional provision of the novel flanged drive member permits accurate and free negotiation of curves and turns in the track without sacrificing any of the precision of the tracking and accordingly of stitching. In addition to this capability to accurate tracing 15 and maintenance of precise stitch length control, the present invention permits the tracing of patterns having relatively sharp changes in direction and having intersecting lines of stitches.

While the invention has been disclosed and described in some detail in the drawings and foregoing description, 25 they are to be considered as illustrative and not restrictive in character, as modifications may readily suggest themselves to persons skilled in this art and within the broad scope of the invention, reference being had to the appended claims.

The invention claimed is:

1. A drive mechanism for a quilting machine or the like, comprising:
  - (A) a pattern track assembly including
    - (1) a base plate and
    - (2) a track secured to said base plate and arranged to present an elongate row of teeth extending in a pattern having straight sections and curved sections; and
  - (B) a drive head having
    - (1) a track tooth-engaging member,
    - (2) an input shaft,
    - (3) drive means coupling said tooth-engaging member to said input shaft and including
      - (a) a pair of wheel-like flanges arranged, one on each side of said tooth-engaging member, to maintain the engagement of said member with said track,
      - (1) said flanges being relatively movable toward and away from each other, and
    - (4) resilient means biasing one flange toward the other.
2. A motor-driven follower of the type used for shifting a quilting machine carriage means in accordance with

the straight and curved sections of a pattern-forming track traversed by the following, comprising:

- (A) a follower housing; and
- (B) a drive train supported by said housing and including
  - (1) a power input shaft extending into said housing,
  - (2) a track-engaging gear mounted for rotation about a transverse axis,
  - (3) interconnecting means for driving said track-engaging gear from said input shaft, and
  - (4) a pair of wheel-like flanges,

- (a) one mounted on each side of said gear for rotation about the axis of said shaft,
- (b) one of said flanges being axially movable in relation to the other to provide a variable axial spacing between said flanges.

3. The follower of claim 2 including

- (A) resilient means interposed between said housing and said movable flange to bias said movable flange toward said other flange.

4. A pattern track for a quilting machine or the like comprising:

- (A) a base plate; and
- (B) an elongate track secured to said base plate,

- (1) said track being composed of an elongate strip of material
  - (a) which has straight and curved sections and intersections corresponding to the straight and curved sections and intersections of a desired quilt-stitching pattern,
  - (b) which presents, between intersections, an upper edge notched to provide a uniform succession of teeth, and
  - (c) which has, at one intersection,
    - (1) one track section of the strip extending continuously through the intersection with one tooth centered on that intersection and with its upper margin cut away to eliminate one tooth on each side of said centered tooth and
    - (2) the other track section of the strip arranged with one tooth centered on that intersection and with its upper margin cut away to eliminate the centered tooth and one tooth on each side thereof.
